UNITED STATES PATENT OFFICE.

IRWIN E. DEARSLEY, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed December 4, 1925. Serial No. 73,187.

This invention relates to lifting jacks, and more particularly to a jack designed for use about garages and repair shops, for quickly and easily lifting heavy loads, such as one end of an automobile, and transporting the elevated load from place to place.

In general, the jack comprises a rather long, low truck or carriage, supported at its ends on small rollers, all of the mechanism carried by the carriage being of very small height, or capable of being depressed to an extremely low position, so that the assembly can be pushed under very low hanging loads, such as automobiles mounted on the new balloon tires. The forward end of the carriage, which is to be pushed under the load, carries the actual lifting mechanism of the jack, while the driving and reversing mechanism for actuating the lifting jack in both directions is mounted at the extreme rear end of the carriage, so that it may be conveniently operated.

One object of the invention is to provide a jack of the type described, which is extremely low, so as to operate beneath very low hanging loads, and at the same time may be conveniently operated from a distance.

Another object is to provide a new and improved form of lifting mechanism having an extremely low initial position, and a relatively high operative range of movement.

Another object is to provide an improved adjustable operating handle, whereby the mechanism may be operated from a number of different convenient positions.

Another object is to provide an improved form of reversing mechanism, whereby the same movement of the operating handle may be used to elevate or lower the jack as desired.

Another object is to provide an improved form of foot operated mechanism for quickly elevating the jack before the load is accepted.

Another object is to provide an improved automatic reversing mechanism, whereby continuous operation of the lifting handle will cause the jack to be lowered after it has reached its extreme limit of elevation.

Numerous other objects and advantages of this invention will be apparent from the following detailed description of one approved form of the apparatus.

In the accompanying drawings: 55
Fig. 1 is a side elevation of the complete jack.

Fig. 2 is a plan view.

Fig. 3 is a side elevation of the front, or lifting end of the jack, on a much larger 60 scale.

Fig. 4 is a longitudinal vertical section, through the elevating and reversing mechanism.

Fig. 5 is a horizontal section, taken substantially on the line 5—5 of Fig. 4.

Fig. 6 is a side elevation of the rear end of the jack, taken from the side opposite Fig. 1.

Fig. 7 is a vertical section, taken substantially on the line 7—7 of Fig. 4.

Figs. 8 to 16 are detail views of certain parts of the elevating and reversing mechanism showing the same elements in different operating positions. Figs. 8 and 9 show 75 the parts positioned for elevating the jack, whereas Figs. 10 to 16 inclusive show successive steps in the lowering process.

The frame 1 is built up of suitable castings and connecting members and is of such 80 a length that when the lifting end is positioned beneath one of the axles of an automobile, the other end on which is positioned the operating mechanism, will extend out to an accessible position beyond the body 85 of the car. The front or lifting end of the carriage 1 is supported upon a pair of rather small, but sturdy rollers 2, mounted on the ends of a transverse axle 3. The rear end of the carriage is supported by a pair 90 of small rollers or casters 4, pivoted at the lower end of vertical stub shafts 5, which are swiveled in brackets 6 extending from the respective sides of the carriage 1. These swiveled casters 4 permit steering of the 95 carriage, which can be swung around abruptly into any desired position.

The lifting head 7 has a screw threaded stem 8 mounted in a nut 9, which is seated in a recess in the lifting block 10. By manually rotating the load-carrying head 7, a certain amount of initial adjustment of the lifting head is permitted to adapt the device for loads of different character. The nut 9 may pivot in the block 10 at all times, thus 100 permitting turning movement of the carriage beneath the load, even when the screw 8 is completely raised or lowered. A lug 11

on block 10 is pivoted on journal 12 between the forked end portions of the longer arm 13 of the bellcrank 14, which is suspended from and fulcrumed on the transverse shaft 15, which is mounted in the highest portions of the side members of frame or carriage 1. The shorter arm 16 of the bellcrank 14 is pivoted at 17 to the front end of the push rod or operating bar 18, which terminates near its rear end in a rack bar 19, which meshes with the driving pinion 20 herein-after described. A lug 21 at the front of lifting block or head 10 is pivoted at 22 between the forward ends of a pair of similar links 23, the rear ends of the links being pivoted at 24 to the side members of frame 1. The spacing of shafts 15 and 24 is the same as that of journals 12 and 22, and the links 23 are of the same length as the longer arm 13 of the bellcrank, so that when lifting bellcrank 14 is swung about its pivot 15, the load supporting head 7 will be moved vertically, but will remain horizontal at all times, one elevated position of the load supporting head being indicated in dotted lines in Fig. 3. It will be noted that when the load supporting head is in its completely lowered position, as indicated in full lines in Fig. 3, its upper surface is no higher than the tops of the rollers 2, so that any load can be elevated under which the supporting rollers 2 can be pushed.

The driving pinion 20 is fixed to a transverse shaft 25, journaled in suitable bushings 26 and 27 in the side frames of the carriage 1. The rack bar 19 is slidably supported on a lower transverse bridge portion 28 of the carriage, whereby the rack is held up into engagement with the pinion 20. A yoke or housing 29 has its side arms pivoted about the axle 25 at either side of the driving pinion 20. A ratchet wheel 30 is secured to the shaft 25 at one side of housing 29, and a lifting pawl 31 which cooperates with this ratchet wheel is mounted in an extension 32 at one side of the housing 29. A spring 33 holds the pawl 31 yieldably in engagement with the ratchet 30. A locking pawl 34, pivoted on transverse shaft 35 in frame 1, is also held yieldably in engagement with ratchet 30 by means of spring 36. It will be noted that as the housing 29 is oscillated back and forth, through a short arc, the ratchet 30 will be rotated intermittently in one direction (clockwise, Fig. 4), by the driving pawl 31, and will be held in advanced position against retrograde movement by the locking pawl 34. By means of a mechanism for controlling the pawls 31 and 34, herein-after described, the same oscillatory movement of housing 29 may be used to permit rotation of the ratchet 30 in the opposite direction.

The operating handle 37, in the form of side plates connected by suitable spacing

members, has its lower ends journaled at 38 on the projecting ends of shaft 25 at the outer sides of the frame 1. Handle 37 is of sufficient length to be conveniently operated by a man standing erect, and this handle is used both to oscillate the driving housing 29, and also to move the carriage 1 from place to place. A plunger 39, mounted in a bridging member 40 in the handle 37, is normally projected by spring 41 into one of several holes or openings 42, in the upper portion of yoke or housing 29. This plunger 39 serves to lock the housing 29 and operating handle 37 together to operate as a unit, and by properly selecting the opening 42 with which the plunger is engaged, the inclination of the handle 37 may be varied to suit the convenience of the operator, or to avoid overhanging obstructions. A handle 43 at the upper end of plunger 39 may be used to retract the plunger against the spring 41, and a guide arm 44 extends back from the outer end of handle 43 through a suitable aperture in the bridge plate 40. When the plunger 39 is withdrawn, the handle 43 may be slightly rotated to bring the arm 44 out of alignment with the hole in bridge 40, whereby the arm 44 will cooperate with bridge 40 to retain the plunger 39 in withdrawn position. The handle 37 is then free to swing up or down as far as desired for convenience in moving the carriage 1 from one position to another.

The reversing member or plate 45 is freely pivoted about the axis of shaft 25 at 100 the side of ratchet wheel 30 opposite the housing 29. Reversing plate 45 has a cam extension 46 at one side adapted to cooperate with a pin 47 on locking pawl 34, and has a second cam extension 48 at the other side of its axis, adapted to cooperate with a pin 49 on the lifting pawl 31. A compression spring 51, confined between a portion of the carriage 1 and a lug 50 on the reversing member 45, tends to rotate the reversing member in a clockwise direction, (as seen in Figs. 8 to 16 inclusive), and movement of the reversing plate in this direction is limited by the engagement of lug 52 on the reversing plate with a fixed stop 53 on carriage 1. When the jack is to be elevated, reversing member 45 is held back against the action of spring 50 so that cams 46 and 48 will not encounter the pins 47 and 49 on the pawls 34 and 31. This position of the parts is indicated in Figs. 8 and 9. As best indicated in Fig. 6, a cam or crank arm 54, pivoted in the carriage frame at 55, is adapted to be moved up behind the lug 56 on the reversing member 45, to hold this member in inoperative position as in Figs. 8 and 9. A second crank arm 57, connected with cam 54, has a pin 58 at its free end engaging in a slot 59 in one arm of a pedal lever 60, pivoted on the end of shaft 25, 130

By depressing pedal 61, at the end of one arm of lever 60, the bellcrank composed of crank arms 54 and 57, is thrown up into the position indicated in Fig. 6, bringing the 5 cam 54 behind the lug 56, and moving the reversing plate 45 against the action of spring 51, to its inoperative position. Oscillating movement of hand lever 37 will then serve to rotate ratchet 30 in a clockwise 10 direction, as seen in Figs. 8 and 9, to effect an elevation of the jack. It will be understood that the load carried by the supporting head 7, acting through bellcrank 14 and push-rod 18 and rack bar 19, constantly 15 tends to rotate the driving pinion 20 and the ratchet wheel 30 in a counter clockwise direction, as shown in Figs. 8 to 16 inclusive. As shown in Fig. 8, the handle 37 has been elevated, and the locking pawl 34 is in engagement with a tooth of ratchet 30 and is 20 holding the load. As the hand lever 37 is swung down from the position shown in Fig. 8 to that shown in Fig. 9, the lifting pawl 31 will be brought into engagement with a tooth or ratchet wheel 30 and will 25 partially rotate this ratchet, the locking pawl 34 riding up against the action of spring 36 until it snaps into engagement with the next following tooth of the ratchet. 30 When hand lever 37 is swung back up to the position shown in Fig. 8, the ratchet 30 will be held against retrograde movement by the locking pawl 34 and the lifting pawl 31 will ride out against the action of spring 35 33 until it snaps into engagement with the next following pawl on the ratchet wheel. Successive oscillations of the operating handle 37 will repeat this cycle of events, advancing the ratchet 30 each time through an 40 arc equal to one tooth of the ratchet wheel. Obviously, the parts could be so proportioned that this advance would be through an arc equal to a plurality of teeth.

Referring now to Figs. 10 to 16 successive 45 steps in the lowering process will be described. It should be understood that the reversing plate 45 is now released from the cam 54, so that it is free to swing in a clockwise direction under the influence of spring 51. As shown in Fig. 10, the load is being 50 held by the locking pawl 34, which is in engagement with a tooth of ratchet 30, and the cam 46 on the reversing plate 45 is held up against the pin 47 on pawl 34, by the 55 spring 51. The hand lever 37 is being swung down and pin 49 on lifting pawl 31 has just snapped off from the end of cam 48 permitting the end of the lifting pawl to 60 engage with one of the teeth on ratchet 30 near its upper surface. Further downward movement of handle 37 will cause the pawl 31 to slide down the inclined surface of this tooth until it engages with the next successive tooth and accepts the load. A slight 65 further clockwise or downward movement 70 of operating handle 37 will cause a slight clockwise rotation of ratchet wheel 30, and thus release the load from locking pawl 34, which will now be snapped out to an inoperative position by the cam 46 acting under the influence of spring 50. This position of the parts is shown in Fig. 11. It will be noted that the reversing plate 45 has been 75 swung in a clockwise direction until the stop lug 52 has engaged with the fixed stop 53, but the cam 48 is still out of engagement with the pin 49 on lifting pawl 31. The load is now held by the lifting pawl 31 and handle 37. The hand lever 37 is now elevated, allowing the ratchet wheel 30 to move 80 back with it in a counter clockwise direction. During this upward movement, the pin 49 on pawl 31 first comes into engagement with the cam 48, as shown in Fig. 12, and subsequent upward movement of these parts, 85 causes the reversing plate 45 to share the counter clockwise rotation of the ratchet 30, gradually moving the cam 46 down out of engagement with the pin 47 on locking pawl 34, as shown in Fig. 13. Eventually the locking pawl 34 will engage with the tooth of the ratchet wheel next following that with which it was previously engaged, and will accept the load, and prevent further 90 clockwise movement of the ratchet 30. As soon as the load is released from the lifting pawl 31, it will be snapped out of engagement with the ratchet wheel by the action of cam 48 against pin 49 on the pawl, and the pawl will ride up to the inoperative 95 position shown in Fig. 15. This indicates the limit of the upward swing of the operating lever 37. As we start down again on the succeeding downward swing of the operating lever, pin 49 will ride off from the cam 48 allowing the spring 33 to bring the lifting pawl back into engagement with the ratchet as indicated in Fig. 16, from which 100 position of the parts they move directly to the initial position shown in Fig. 10, and the cycle of events just described is repeated. It will thus be seen that successive oscillations of the operating handle 37 will cause 105 the load to be lowered step by step, just as it was elevated by similar movements of the operating handle when the reversing member was in inoperative position as shown in Figs. 6, 8 and 9.

Projecting from one side of the extreme 110 rear end of rack bar 19 is a lug 64, which, upon extreme inward movement of the rack bar will engage with one arm 65 of a lever centrally pivoted at 66 in the carriage frame, the other arm 67 of this lever resting in engagement with a pin 68 on one side of cam 54. Further inward movement of the 115 rack bar and lug 64 will swing the lever 65 in a clockwise direction, as seen in Fig. 6 and push the cam 54 down out of engagement 120 with the lug 56, thus releasing the reversing 125 member. This will permit the cam 46 to move 130

member 45, so that successive operations of the operating handle 37 will cause the load to be lowered as hereinabove described. The cam 54 may be manually released at any time by pushing pedal 63 to the right as shown in Fig. 6.

On the opposite end of the drive shaft 25 is secured a "paddle" wheel 69, comprising a plurality, (preferably four), of spaced arms 70, each having a pedal 71 at its outer end whereby a pressure of the foot on one of the pedals will give a partial clockwise rotation to the shaft 25. Although the leverage is small, this mechanism is adapted to quickly bring the lifting head 7 up to meet the load, after which the actual elevation of the load is carried on by means of the longer hand-lever 37.

In the general operation of this device the front end of the jack is shoved into position beneath the load by suitably manipulating the operating handle 37. If the load to be engaged is somewhat higher than usual above the floor or other supporting surface, the supporting head 7 is first rotated within the nut 9 to elevate this head above the supporting block 10 before the jack is pushed into position beneath the load. Now by successively pushing down upon the pedals 71 the mechanism may be quickly operated to bring the supporting head 7 up into engagement with the load. The rotation of driving pinion 20 pushes the rack bar 19 inwardly or forwardly, thus swinging up the front end of bellcrank 14 and elevating the head 7. After the load has been accepted, further elevation is accomplished by oscillating the hand lever 37 through a short arc. For this operation, the handle 37 may be positioned at a convenient angle by withdrawing the plunger 39, by means of handle 43, and placing this plunger in that opening 42 which will leave the handle at the most favorable angle. If the reversing member 45 is in operative position, it may be thrown out by depressing the pedal 61 to the position shown in Fig. 6. When the load has been elevated to the desired position, it will be held in this position by the locking pawl 34. If the load is to be moved bodily, as when one end of an automobile is to be shifted to a different position in a garage, the jack and the load carried thereby may be moved as desired by means of the handle 37, which may be kept locked to housing 29 or conveniently released from the operating housing 29 by withdrawing the plunger 39 and positioning the arm 44 against the bridge member 40, thus holding the plunger 39 in retracted position. When it is desired to lower the load, it is only necessary to push over the pedal 63, thus releasing the reversing plate 45, so that subsequent reciprocation or oscillation of the operating handle 37 will cause the load to be lowered step by step.

If the load has been elevated to or near the extreme upward limit of the jack's movement, it will be unnecessary to manipulate the pedal 63, since continuous oscillation of the hand lever 37 will bring the lug 64 on rack 19 into engagement with lever 65, thus automatically throwing the reversing member into operative position.

The oscillatory travel of the housing 29 is limited at the end of the downward stroke by the engagement of the lug 72 on housing 29 (see Fig. 8), with the floor 73 of the bridge member 28 of frame 1 (see Fig. 7), and at the end of the upward stroke by the engagement of the top of lug 72 with an upper portion of the frame 1. This limits the motion of the handle 37 to a comparatively small arc when it is locked to the housing 29 by the plunger 39, and is of great assistance to the operator when placing the jack in any position under a load, for by a short movement up or down of the handle 37, a contact is formed with the main-frame 1, thus establishing a rigid unit which may be moved around with ease.

A safety feature that should not be overlooked is that when the operator has the load lifted and desires to work underneath it, he can, by pulling the plunger 39 out of hole 42 and locking it out by engagement of leg 44 with the plate 40, disconnect handle 37 so that no accidental movement of the handle will operate the jack and lower the load on top of the operator.

I claim:

1. In a lifting jack, an elevating and lowering mechanism comprising a pivoted reversing member, a means for automatically rotating the member in one direction, a locking cam for moving the member in the opposite direction against the action of the means to an inoperative position, and a lever pivoted on the axis of the reversing member and adapted to operate the cam.

2. In a lifting jack, an elevating and lowering mechanism comprising a pivoted reversing member, a pair of lugs on the member, a means engaging one lug to automatically rotate the member to an operative position, a rotary cam adapted to be swung into position behind the other lug to move the reversing member to inoperative position and lock it there, a crank-arm on the cam, and a lever pivoted on the axis of the reversing member and having an operating connection with the crank arm to swing the cam into or out of engagement with the lug.

3. In a lifting jack, the combination with an elevating and lowering mechanism including a ratchet wheel, a lifting pawl and a locking pawl engageable with the ratchet, springs for normally holding these pawls in engagement with the ratchet, and means for oscillating the lifting pawl about the periphery of the ratchet, of a reversing mem-

- ber pivoted on the axis of the ratchet and having a pair of cams adapted to alternately move the pawls out of engagement with the ratchet.
4. In a lifting jack, the combination with an elevating and lowering mechanism including a ratchet wheel, a lifting pawl and a locking pawl engageable with the ratchet, and means for oscillating the lifting pawl about the periphery of the ratchet, of a reversing member pivoted on the axis of the ratchet and having a pair of cams adapted to alternately move the pawls out of engagement with the ratchet, and a means for urging the reversing member in one direction.
5. In a lifting jack, the combination with an elevating and lowering mechanism including a ratchet wheel, a lifting pawl and a locking pawl engageable with the ratchet, means for oscillating the lifting pawl about the periphery of the ratchet, of a reversing member pivoted on the axis of the ratchet and having a pair of cams adapted to alternately move the pawls out of engagement with the ratchet, a spring for moving the reversing member in one direction, a stop for limiting this movement of the reversing member, and means for locking the reversing member in retracted position against the action of the spring.
6. In a lifting jack, the combination with an elevating and lowering mechanism including a ratchet wheel, a lifting pawl and a locking pawl engageable with the ratchet, means for oscillating the lifting pawl about the periphery of the ratchet, of a reversing member pivoted on the axis of the ratchet and having a pair of cams adapted to alternately move the pawls out of engagement with the ratchet, a means for moving the reversing member to operative position, a lug on the member, and a cam movable behind the lug to lock the reversing member in inoperative position.
7. In a lifting jack, the combination with an elevating and lowering mechanism including a ratchet wheel, a lifting pawl and a locking pawl engageable with the ratchet, means for oscillating the lifting pawl about the periphery of the ratchet, of a reversing member pivoted on the axis of the ratchet and having a pair of cams adapted to alternately move the pawls out of engagement with the ratchet, a means for moving the reversing member to operative position, a lug on the member, a rotatable cam movable behind the lug to lock the reversing member in inoperative position, and a lever for shifting the cam.
8. In a lifting jack, the combination with an elevating and lowering mechanism including a ratchet wheel, a lifting pawl and a locking pawl each having an outstanding projection, springs for yieldably holding each pawl in engagement with the ratchet, and means for moving the lifting pawl back and forth about the periphery of the ratchet, of a reversing member pivoted on the axis of the ratchet and having a pair of cam surfaces adapted to engage the projections to move the pawls away from the ratchet, and a means for automatically rotating the reversing member in one direction.
9. In a lifting jack, the combination with an elevating and lowering mechanism including a ratchet wheel, a lifting pawl and a locking pawl each having an outstanding projection, springs for yieldably holding each pawl in engagement with the ratchet, and means for moving the lifting pawl back and forth about the periphery of the ratchet, of a reversing member pivoted on the axis of the ratchet and having a pair of cam surfaces adapted to alternately engage the projections to move one or the other of the pawls out of engagement with the ratchet.
10. In a lifting jack, the combination with an elevating and lowering mechanism including a ratchet wheel, a lifting pawl and a locking pawl each having an outstanding projection, springs for yieldably holding each pawl in engagement with the ratchet, means for moving the lifting pawl back and forth about the periphery of the ratchet, of a reversing member pivoted on the axis of the ratchet and having a pair of cam surfaces adapted to alternately engage the projection to move one or the other of the pawls out of engagement with the ratchet, a means to urge the reversing member to operative position, and a means for locking the reversing member in retracted position whereby the cams are held out of engagement with the projections.
11. In a lifting jack, the combination with an elevating and lowering mechanism including a ratchet wheel, a lifting pawl and a locking pawl each having an outstanding projection, springs for yieldably holding each pawl in engagement with the ratchet, means for moving the lifting pawl back and forth about the periphery of the ratchet, of a reversing member pivoted on the axis of the ratchet and having a pair of cam surfaces adapted to alternately engage the projections to move one or the other of the pawls out of engagement with the ratchet, a pair of lugs on the reversing member, a spring engaging one lug to move the reversing member in one direction, and a locking cam engageable with the other lug to move the reversing member in the opposite direction.
12. In a lifting jack, an elevating and lowering mechanism comprising a longitudinally movable member and rotary means for moving this member in either direction,

- a reversing member cooperating with the rotary means to determine the direction of movement of the longitudinally movable member, and means on the longitudinally movable member for rendering the reversing member operative when the longitudinally movable member reaches its limit of movement in one direction.
13. In a lifting jack, an elevating and lowering mechanism comprising a longitudinally movable member and rotary means for moving this member in either direction, a reversing member cooperating with the rotary means to determine the direction of movement of the longitudinally movable member, means for locking the reversing member in inoperative position, and means on the longitudinally movable member for unlocking the locking means.
14. In a lifting jack, an elevating and lowering mechanism comprising a longitudinally movable rack-bar, a rotary shaft, a pinion on the shaft meshing with the rack, a pawl and ratchet mechanism for rotating the pinion, a reversing member pivoted about the shaft for controlling the direction of rotation of the pinion, a cam for locking the reversing member in inoperative position, a lever for releasing the cam, and a lug on the rack-bar engaging the lever in one position of the rack.
15. In a lifting jack, an elevating and lowering mechanism comprising a longitudinally movable rack-bar, a rotary shaft, a pinion on the shaft meshing with the rack, a pawl and ratchet mechanism for rotating the pinion, a reversing member pivoted about the shaft for controlling the direction of rotation of the pinion, a cam for locking the reversing member in inoperative position, and means operated by the rack-bar at one extremity of its movement for releasing the cam.
16. In a lifting jack, an elevating and lowering mechanism comprising a longitudinally movable rack-bar, a rotary shaft, a pinion on the shaft meshing with the rack, a pawl and ratchet mechanism for rotating the pinion, and an auxiliary means for rotating the pinion comprising a plurality of arms secured to the shaft.
17. In a lifting jack, an elevating and lowering mechanism comprising a longitudinally movable rack-bar, a rotary shaft, a pinion on the shaft meshing with the rack, and a pawl and ratchet mechanism for rotating the pinion, and an auxiliary means for rotating the pinion comprising a plurality of arms secured to the shaft, and a pedal at the free end of each arm.
18. In a lifting jack, an elevating and lowering mechanism comprising a rotary shaft, a plurality of radially extending crank-arms secured to the shaft, and a pedal at the free end of each arm.
19. In a lifting jack, an elevating and lowering mechanism comprising a rotary shaft, an oscillatable member pivoted about this shaft for actuating the elevating means, an operating handle also pivoted about the shaft, and means for locking the handle to the member in different selected positions.
20. In a lifting jack, an elevating and lowering mechanism comprising a rotary shaft, an oscillatable member pivoted about the axis of this shaft for actuating the elevating means, an operating handle also pivoted about the axis of the shaft, a spring-pressed plunger carried by the handle, a plurality of openings in the oscillatable member to be selectively engaged by the plunger, and a locking means for holding the plunger withdrawn from the openings against the action of the spring.
21. In a lifting jack, an elevating and lowering mechanism comprising a rotary shaft, an oscillatable member pivoted about the axis of this shaft for actuating the elevating means, an operating handle also pivoted about the axis of the shaft, a spring-pressed plunger carried by the handle, a plurality of openings in the oscillatable member to be selectively engaged by the plunger, and a handle on the plunger for withdrawing it from an opening, the handle being movable to lock the plunger in withdrawn position.

IRWIN E. DEARSLEY.
